UNITED STATES PATENT OFFICE

121,445

DESIGN FOR A DRESS ENSEMBLE

Margaret Hobgood, New York, N. Y.

Application June 17, 1940, Serial No. 93,061

Term of patent 3½ years

To all whom it may concern:

Be it known that I, Margaret Hobgood, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a front view of the dress member.

Fig. 4 is a rear view of Fig. 3.

I claim:

The ornamental design for a dress ensemble, as shown.

MARGARET HOBGOOD,
